UNITED STATES PATENT OFFICE.

MARTIN E. McGRATH, OF RIO GRANDE, OHIO.

RAILWAY-SLEEPER.

No. 800,284

Specification of Letters Patent. Patented Sept. 26, 1905.

Application filed June 2, 1905. Serial No. 263,438.

To all whom it may concern:

Be it known that I, MARTIN E. McGRATH, a citizen of the United States, residing at Rio Grande, in the county of Gallia and State of Ohio, have invented new and useful Improvements in Railway-Sleepers, of which the following is a specification.

This invention relates to railroad-tracks, and includes a sleeper or sill made of cement, hard-burned clay, or other plastic material, together with other improved means for supporting and maintaining in proper position the rails of the railway.

In the accompanying drawings, Figure 1 is a plan view of a section of track constructed according to this invention. Fig. 2 is an end or sectional view of the track. Fig. 3 is an enlarged vertical cross-section of one of the sills.

Referring specifically to the drawings, the rails of the track are indicated at 6. The sleepers are made of clay or cement, as above indicated, and each consists of a block of suitable size—say three feet long, fourteen inches wide, and nine inches deep—which extends longitudinally under the rail. The block so formed is indicated at 7, and it has in its top a seat 8 to receive a wooden plate or block 9, upon which the base of the rail sits. The sill 30 is irregular in cross-section to give it a hold in the earth. It has at the bottom a longitudinal rib 10 and at the sides longitudinal grooves 11 below the surface of the ground, being spread or flared outwardly below the grooves, as at 12, so as to prevent lift. The longitudinal rib 10 serves to prevent side slip, and the ribs 13, extending along the sill above the groove at the surface of the ground, assist in holding the sill in place.

The sill has two longitudinal hollows or recesses in the body thereof, (indicated at 14,) and these connect with bolt-holes, through which the bolts 15 extend to the top of the sill. The bolts may be inserted or removed through the holes 14. Said bolts hold the rail 45 in place by means of the clips 16, which overlie the flanges of the base of the rail.

The rails are prevented from spreading by tie-bars 17 of known construction, which are located and grip the bases of the opposite rails between the sills. These tie-bars may be of the usual construction, such as those used to connect switch-points.

The wooden plate 9 serves to cushion the shock of the rail and prevent fracture of the 55 sleeper.

The sleeper gives a large surface-bearing for the rail and on account of its shape is easy to keep in line. The sleepers are fireproof and can be molded at small cost. They may 60 be applied to existing tracks by the substitution thereof for worn-out wooden ties.

What I claim as new, and desire to secure by Letters Patent, is—

1. A sleeper for railroads, comprising a hollow block of plastic material adapted to extend lengthwise under the rail and having a longitudinal recess in the top, in which the rail rests, and ground-engaging ribs. 65

2. A sleeper comprising a hollow block having a longitudinal depression in the top in which the rail rests and ground-engaging ribs and grooves in the bottom and sides, and bolt-holes extending upwardly from the hollow 70 through the top of the block.

In testimony whereof I have signed my name to this specification in the presence of two subscribing witnesses.

MARTIN E. McGRATH.
